UNITED STATES PATENT OFFICE.

REGINALD L. S. DOGGETT, OF EAST ORANGE, NEW JERSEY.

DESIGN FOR A DOOR KNOCKER OR SIMILAR ARTICLE.

Application filed November 20, 1926. Serial No. 19,798. Term of patent 14 years.

To all whom it may concern:

Be it known that I, REGINALD L. S. DOGGETT, a citizen of the United States, and a resident of East Orange, in the county of Essex and State of New Jersey, have invented a new, original, and ornamental Design for a Door Knocker or Similar Article, of which the following is a specification, reference being had to the accompanying drawing, forming part thereof.

Figure 1 is a front elevation of a door knocker or similar article showing my design, and

I claim:

The ornamental design for a door knocker or similar article, as shown.

REGINALD L. S. DOGGETT.
